UNITED STATES PATENT OFFICE.

ALBRECHT GRAEF, OF NEW YORK, N. Y.

DESIGN FOR A RAZOR-BLADE.

SPECIFICATION forming part of Design No. 32,057, dated January 2, 1900.

Application filed December 6, 1899. Serial No. 739,445. Term of patent 7 years.

To all whom it may concern:

Be it known that I, ALBRECHT GRAEF, a citizen of the United States, residing at New York, in the borough of Manhattan and State 5 of New York, have invented and produced a new and original Design for Razor-Blades, of which the following is a specification, reference being had to the accompanying drawing, forming a part thereof, which drawing 10 shows a side elevation of a razor-blade embodying the design.

As shown in the drawing, the leading feature of the design is a shield bearing the bust of a man and two flags arranged in connection therewith.

A indicates a shield provided with stars and bars and having a central portion a, simulat-

ing a heart in general appearance and containing the bust B of an oriental. Flags C C' are arranged at each side of the shield A and 20 the poles d of the same converge at the lower part of the shield. At each side of the shield are arranged twigs or foliage e, on which birds f are perched.

What I claim is—

25 The design for a razor-blade, as herein set forth.

In testimony that I claim the foregoing as my invention I have signed my name in presence of two subscribing witnesses.

ALBRECHT GRAEF.

Witnesses:

PAUL GOEPEL,
M. H. WURTZEL.
